UNITED STATES PATENT OFFICE.

WILLIAM COBURN AND CHARLES W. DAVIS, OF SEATTLE, WASHINGTON, ASSIGNEES
OF ONE-THIRD TO JULES MAES, OF SEATTLE, WASHINGTON.

ACETYLENE-GENERATOR.

1,196,336.

Specification of Letters Patent. Patented Aug. 29, 1916.

Application filed June 1, 1915. Serial No. 31,442.

To all whom it may concern:

Be it known that we, WILLIAM COBURN and CHARLES W. DAVIS, citizens of the United States, and residents of Seattle, in the county of King and State of Washington, have invented certain new and useful Improvements in Acetylene-Generators, of which the following is a specification.

Our invention relates to lanterns, and consists of a construction wherein an acetylene generator is incorporated in the lantern, the construction being novel in many features.

The object of our invention is to provide an improved construction of such parts whereby the efficiency and convenience of handling may be increased.

The scope of the invention may be determined by an inspection of the claim terminating this specification.

20 The drawing accompanying herewith shows the preferred form of construction.

The frame work 4 and the glass globe 40 may all be of any suitable or standard construction. Secured in the lower part of the frame 4 is a cup-like casing 3, the lower portion of which is somewhat reduced in diameter to form a shallow cup 30, of a diameter fitting over the lower end of the acetylene generator used.

30 The generator is divided into two principal parts, the lower part 1 being of cup shape, and constituting the carbid chamber, and the upper part 2 constituting the water tank. The two parts are secured together, as by threaded sections at 12, and the joint between them made tight by the use of a gasket or packing ring 13. A tubular pillar 5 is axially placed, and extends through the water tank without communicating with the

40 interior thereof. This forms a conducting channel for the gas from the carbid or generating chamber 1 to the burner 6, the burner being mounted on top of the water tank. The upper part 50 of this tubular pillar is enlarged somewhat and contains a layer 51 of gas-screening material, which material may be a wad of fibrous cotton, or like material.

50 The gas conveying channel is extended downwardly by a tube 7 which extends close to the bottom of the carbid chamber. The lower end of this tube is open, but may have a screen across this end if desired. The gas

is admitted to the tube 7 through orifices 70 located just below the part of the water tank 55 2 into which the tube enters.

Water is admitted from the tank 2 into the chamber 1 through a passage 9 which passage is controlled by a needle valve 90, the stem of which extends laterally and projects from the generator, being provided with a knob 91 by which it may be conveniently operated. The water admitted through the passage 9 is delivered to a tube 8 which branches from the tube 7. By this construction the water is admitted, not upon the top of the mass of carbid, but at the bottom thereof. Should any particle of carbid enter through the gas admission openings 70, these will fall to the bottom of the tube 7, 70 where they will quickly become decomposed by the water admitted through the tube 8. The water tank is provided with a removable plug 20, through which it may be charged.

75 The case surrounding the generator is spaced outwardly therefrom. Air is admitted to the chamber thus formed through openings 31 at the lower part thereof, and admitted to the space within the globe 40 80 through holes formed in a flange 32 which projects inwardly and contacts with the generator at a higher level, thereby holding the same securely in position.

By reason of the above construction water is admitted to the lower part of the mass 85 of carbid, while the gas is drawn off through the openings 70, which are above the level of the carbid.

Having now described our invention, what 90 we claim and desire to secure by Letters Patent of the United States is:

An acetylene generator comprising a cup-like carbid chamber, a water tank above said carbid chamber adapted to screw upon and close the same, a tubular gas delivery pillar extending upward through the water tank, and axially placed therein, a burner upon the upper end of said pillar, a tube secured in the bottom of said water tank and forming a downward extension of and communicating directly with the channel of said pillar, said tube projecting well within said carbid chamber, but not to the base thereof, and being open at its lower end, said tube 100 105 being also provided with gas inlet openings

near the upper edge of the carbid chamber and above the level of the carbid, a water delivery channel in the base of said water tank, a valve therein controlling said channel, and a second tube communicating with said water channel and extending well into said carbid chamber, said second tube com-

municating with said first tube well below the gas inlet openings and below the normal level of the carbid.

Signed at Seattle, Washington, this 26th day of May, 1915. ¹⁰

WILLIAM COBURN.
CHARLES W. DAVIS.
